END LOCK FOR RINGS OF MECHANICAL BINDERS

Clarence D. Trussell, Turnwood, N. Y.

Application August 6, 1949, Serial No. 108,903

3 Claims. (Cl. 129—1)

1

The invention herein disclosed relates to mechanical binders of the type covered in copending patent application Serial No. 602,985, filed July 3, 1945, Patent 2,502,493 of April 4, 1950 involving a strip of sheet material rolled to form a tubular backbone and having integrally attached fingers which can be curled into closed ring formation.

The present invention is concerned with securing the free ends of the fingers in the closed, ring forming relation.

Particular objects of the invention are to provide effective means for locking the free ends of the ring forming strips to the backbone structure, which will automatically interlock by the mere act of closing the rings and which will constitute an integral part of the structure.

Other important objects of the invention are to provide an end lock for the rings which, while of a generally permanent character may, if occasion required, be opened to release the rings, and this without destroying the lock, so that the rings may be again closed and locked.

Further objects of the invention are to provide a lock construction of the type and character indicated which may be provided at low cost and which will be commercially practical in every way.

Other desirable objects and the novel features through which the purposes of the invention are attained are set forth or will appear in the course of the following specification.

The drawing accompanying and forming part of the specification illustrates several different embodiments of the invention. Actual structure, however, may be further modified and changed, all within the true scope of the invention as hereinafter defined and claimed.

Fig. 1 in the drawing is a broken plan view illustrating a portion of a binder blank having the invention incorporated therein;

Fig. 2 is a broken part sectional end view of one of the completed bindings;

Fig. 3 is a broken plan view of the latter, showing two rings completely closed and locked and a third ring, in section, nearly closed and about to be automatically interlocked with the rolled, back portion of the binder;

Fig. 4 is an enlarged broken detail of the interlocking portions of the back and finger structure first shown in Fig. 1;

Figs. 5, 6 and 7 are similar views illustrating other forms of the invention;

Figs. 8 and 9 are broken front and edge views,

respectively, of another embodiment of the invention.

Figs. 1, 2 and 3 show how the binding is made up of a one-piece blank of sheet material comprising an edge strip portion 9 which is rolled into tubular formation, and integrally attached spaced parallel ring forming fingers 10 projecting from one edge of the base strip and having tapered, rounded or bluntly pointed free ends 11 which are inserted through slots provided in the rolled base strip.

The lock for the ring ends is accomplished by momentary deformation and straightening of the tips of the fingers as they pass through the slots, with companion parts located to interlock as the finger tips snap from deformed back to original, generally straight condition.

In the first form of the invention shown in Figs. 1 to 4, the slots in the side of the tubular back 9 have one curved edge 12 and a lug 13 projecting from the opposite edge into the concavity of the curved edge, thus to require the tip of the finger strip to be bent or arched transversely to pass through the slot, as shown in the broken lines in Fig. 4.

The finger or ring forming strip 11 in this first form of the invention has a transverse slot 14 at a short distance from the end of the strip of a length to accommodate the projecting tongue 13 when the strip, in its arched condition, has been forced through the base slot far enough to register with tongue 13. At such time the spring inherent in the normally flat material will cause the finger strip to react and snap into substantially flattened condition with the transverse slot 14 in the finger fitting over the corresponding lug 13 in the base slot.

With this construction it is possible to close and lock the fingers simply by bending them into ring formation and forcing the ends of the same through the curved slots in the base strip. This may be accomplished in special ring closing dies or jigs such as disclosed in copending patent application Serial No. 602,985.

While the lock construction described will hold the rings permanently locked against any accidental or unintentional disengagement, it is nevertheless possible to release the rings by bending the ends of the same into the bowed or arched formation indicated in broken lines, Fig. 4.

Fig. 5 illustrates a variation of the invention in which two short transverse slots 15 and two edge notches 16 are provided in the ring forming strip to engage over diagonally opposite lugs 17 on opposite sides of the base slot and over diag-

onally opposite shoulders 18 at the opposite ends of the base slot, after the finger strip has first been twisted transversely, as shown in broken lines, to pass it through the slot far enough to register with such locking elements.

The embodiment shown in Fig. 6 is like that first illustrated, in that the end of the ring strip must be bowed or arched transversely to pass it through the base slot, but the interlock is accomplished in this instance by short, widely spaced, transverse slots 19 in the strip engageable over correspondingly placed lugs 20 on one edge of the base slot. A projection 21 from the opposite edge of the base slot forces the curvature of the strip into the space between the projecting lugs 20.

The Fig. 7 form of construction is generally similar to that last considered, with the additional feature of a longitudinal slot 22 in the tip portion of the ring strip, giving it greater bendability and therefore facilitating entry of the strip into the tubular base and with an extra transverse slot 23 in the intermediate portion of the ring strip to engage over a companion locking projection 24 on the side edge of the base slot.

The binding disclosed may be made of plastic, sheet metal or other suitable sheet material, and the lock feature may be incorporated at practically no additional cost since it is an integral part of the sheet structure and may be produced at the time of blanking out the sheet material.

The slight deformation, bending or twisting required for passing the ends of the rings through the back slots into interlocked position does not injure or impair the springy character of the normally flat strip sheet material of which the binder is formed. The binder, when closed and locked, may be considered generally as a permanent binder but the structure, nevertheless, permits of the unlocking and opening of the binder rings when or if required.

In Figs. 8 and 9 a more permanent form of interlock is effected by partially severing and bending out an inclined tongue 25 in the end portion of the ring forming strip, which will be pressed back as the end of the strip is forced through the straight slot 26 and will spring out again after passage through the slot, to secure the strip in the ring formation.

What is claimed is:

1. A mechanical binding comprising a strip of normally flat, flexible, springy sheet material rolled into generally tubular formation and having spaced, longitudinally extending slots along one edge portion and spaced, substantially parallel ring forming strips projecting from the opposite edge portion in position to have the free ends of the same enter said slots, said slots being slightly longer than the width of the strips but each having one curved side edge and the opposite side edge provided with a lug projecting into the concavity of the curved edge to enforce transverse arching of said ring forming strips to enter the

same and said free ends of the ring forming strips having openings therein positioned to receive the projecting lugs on the edges of said slots on restoration of said ring forming strips to normal flat shape following the transverse arching of the same required to enter said slots.

2. A mechanical binding comprising a strip of sheet material rolled into generally tubular formation and having spaced, longitudinally extending slots along one edge portion and spaced, substantially parallel ring forming strips projecting from the opposite edge portion in position to have the free ends of the same enter said slots, said slots being shaped to enforce bending of said ring forming strips to enter the same and companion interlocking elements on the edges of said slots and on the end portions of the ring forming strips located to interlock on restoration of said ring forming strips to normal shape following the bending of the same required to enter said slots, and including projections on the edges of the slots imparting transverse curvature to the ring forming strips and said strips having openings to accommodate said projections.

3. A mechanical binding comprising a strip of sheet material rolled into generally tubular formation and having spaced, longitudinally extending slots along one edge portion and spaced, substantially parallel ring forming strips projecting from the opposite edge portion in position to have the free ends of the same enter said slots, said slots being shaped to enforce bending of said ring forming strips to enter the same and companion interlocking elements on the edges of said slots and on the end portions of the ring forming strips located to interlock on restoration of said ring forming strips to normal shape following the bending of the same required to enter said slots, and including projections on the edges of the slots imparting transverse curvature to the ring forming strips and said strips having openings to accommodate said projections, and other openings disposed substantially centrally of the strips for facilitating the transverse bending of the same.
